CLAIM

The ornamental design for a shovel, as shown and described.

DESCRIPTION

FIG. 1 is a perspective view of a first embodiment of a shovel showing my new design;

FIG. 2 is a top plan view thereof;

FIG. 3 is a bottom plan view thereof;

FIG. 4 is a right-side elevation view thereof;

FIG. 5 is a left- side elevation view thereof;

FIG. 6 is a front elevation view, enlarged, thereof; and,

FIG. 7 is a rear elevation view, enlarged, thereof.

The portions shown in broken lines do not form part of the claimed design.

1 Claim, 7 Drawing Sheets
